UNITED STATES PATENT OFFICE

2,528,871

HEADBOARD STRUCTURE FOR BEDSTEADS

Basil C. Deuschle, Southport, Conn., assignor to
 The Fairfield Lumber and Supply Co., Fairfield,
 Conn., a corporation of Connecticut

Application July 19, 1946, Serial No. 684,830

1 Claim. (Cl. 5—183)

1

The present invention relates to a headboard structure for bedsteads, and particularly a headboard of the type adapted to be placed at the head of a bedstead which is not provided with an attached headboard. An object of the invention is to provide a headboard structure which is adjustable as to length, so that it may be used in relation to either a single bed, twin beds, or a double bed, it being particularly proposed to provide a headboard structure having a central section and two side sections having longitudinal telescoping engagement with the central section.

Another object is to provide an adjustable headboard structure having console cabinets mounted upon each of the side sections and adapted to support the adjustable headboard sections between them, the arrangement being such that the length adjustment of the headboard sections correspondingly adjusts the spacing apart of the console cabinets.

A further object is to provide an adjustable headboard structure adapted to be rigidly retained in any position of adjustment, the retaining means being arranged to accurately position the side sections in equally spaced positions at each side of the vertical center line of the central section.

Another object is to provide a headboard structure of simple, economical, and sturdy construction, which lends itself to the incorporation of attractive decorative outlines and surfaces, so that the headboard may be effectually harmonized with various decorative schemes.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a front elevation of a headboard structure, according to the illustrated exemplary embodiment of the invention, the same being shown in its position of adjustment for having a single bedstead associated therewith, the latter being indicated by dot-and-dash lines.

Fig. 2 is a side elevation thereof.

Fig. 3 is a front elevation showing the position of adjustment of the headboard structure for having twin beds associated therewith, the latter being indicated by dot-and-dash lines.

Fig. 4 is a front elevation, showing the headboard structure in its position of adjustment for having a double bed associated therewith, the latter being shown by dot-and-dash lines.

2

Fig. 5 is a fragmentary rear elevation of the headboard, showing one of the side sections in the position of adjustment illustrated in Fig. 4.

Fig. 6 is a transverse vertical sectional view, taken along the line 6—6 of Fig. 4.

Fig. 7 is a transverse vertical sectional view, taken along the line 7—7 of Fig. 4.

Similar reference characters indicate corresponding parts throughout the several figures of the drawings.

Referring to the drawings, the headboard structure, according to the illustrated exemplary embodiment of the invention, comprises a central section, consisting of a rectangular frame 10 having interior grooves 11 along its four sides, in which a rectangular panel-board 12 is engaged and secured. The upper and lower rails of the frame project rearwardly of the panel-board 12 and are provided with inwardly extending longitudinal flanges 13—13 forming between the panel-board and the flanges upper and lower slideways for the two side sections of the headboard, which are adapted to have telescoping inward and outward adjustment movement with respect to the vertical center line of the central section.

The side sections each comprise a three-sided frame 14 consisting of upper and lower horizontal rails and an outer vertical rail, and having interior grooves 15 along its three sides, in which a rectangular panel board 16 is engaged and secured. As shown in Fig. 7 the vertical end rails of the frame 10 of the central section are preferably profiled, as at 17, to fit around the upper and lower rails of the frame 14 and against the front surface of the panel board 16.

To the outer and lower corner portions of each of the side sections there is secured a console cabinet 18 projecting forwardly therefrom and provided with a supporting leg 19, the supporting legs of the two console cabinets constituting the end supports for the telescoping headboard sections extending between them. The central section is preferably provided with a centrally disposed supporting leg 20 adapted to cooperate with the legs 19 to provide equally distributed support in any position of adjustment of the headboard structure.

The side sections are adapted to be fixed in their several positions of adjustment, and for this purpose are each provided with a vertically disposed pin 21 downwardly engaged in a vertical hole 22 in the lower rail of the frame 14 near its inner end, this pin adapted to be dropped into one of several holes 23 provided in predetermined positions along the lower rail of the frame 10 of

the central section. These holes are so positioned that they will position the adjustable side sections in positions of adjustment calculated with regard to the standard widths of different types of beds. As shown in Fig. 1, for instance, one pair of the holes 23 is arranged to position the side sections in their fully contracted position to accommodate a single bed, indicated by the dot-and-dash lines. As shown in Fig. 3, another pair of holes 23 is arranged to position the side sections in their fully extended position to accommodate twin beds, indicated by the dot-and-dash lines. As shown in Fig. 4, still another pair of holes 23 is arranged to position the side sections in an intermediate position of adjustment to accommodate a double bed, indicated by the dot-and-dash lines.

It is pointed out that the frame and panel construction of the central and side sections lends itself to the convenient and effective use of decorative coverings, such, for instance, as quilted fabric, and the like, such coverings being simply placed upon the panels and secured by the frames. Where such coverings are not employed, the panels may be constructed of wood veneer, plastic, or other suitable decorative material. The frames, as well as the consoles, may be varied in design to suit different decorative styles without changing the basic structural and operative features of the headboard structure.

I have illustrated and described a preferred and satisfactory embodiment of the invention, but it will be understood that changes may be made therein, within the spirit and scope thereof, as defined in the appended claim.

What is claimed is:

A self-supporting headboard structure for unattached relatively freely movable self-supporting bedsteads, comprising a central headboard panel section disposed in a vertical plane and having longitudinal guideway means, a pair of side panel sections disposed in a vertical plane and engaged with said guideway means for longitudinal adjustment movement at each side of the vertical center line of said central headboard panel section and each consisting of a normally concealed portion disposed in overlapping relation to said central headboard panel section inwardly of one

side edge thereof and a normally exposed portion projecting beyond said one side edge, and a pair of forwardly extending support members respectively secured to the forward sides of the normally exposed portions of said side panel sections and having forward sides disposed in a vertical plane parallel to and forwardly spaced from the vertical planes of said central and side panel sections, floor engaging means at the underside 10 of said respective support members having floor-engaging surfaces for engaging the floor at points contiguous to both the vertical plane of the side panel sections and the vertical plane of the forward sides of said support members, said side 15 panel sections adapted through inward and outward adjustment to vary the distance between said support members to dispose them at each side of bedsteads of various widths when such bedsteads are respectively arranged forwardly of 20 and contiguous to said central headboard panel section, the normally concealed portions of said side panel sections when extended into exposed relation providing headboard extensions for said central headboard panel section.
